UNITED STATES PATENT OFFICE

CARL J. BJORSON, DONALD W. SIEBERT, AND AARON A. GREENWOOD, OF GARDNER, MASSACHUSETTS, ASSIGNORS TO O. W. SIEBERT COMPANY, OF GARDNER, MASSACHUSETTS, A CORPORATION OF MASSACHUSETTS

CHILD'S CARRIAGE

Application filed November 30, 1931. Serial No. 578,034.

This invention relates to a child's carriage or go-cart of the type commonly known as a "beach cart". Such carts are characterized by relatively light folding running-gear and are usually equipped with bodies largely made of canvas or some other textile or flexible material.

It is the general object of our invention to provide a child's carriage or go-cart having certain novel features of construction by which the utility and convenience of the vehicle is substantially improved.

More specifically, one feature of our invention relates to the provision of a body which is detachably and reversably secured on the running-gear of the vehicle, so that it may be readily removed or reversed in position.

A further feature of our invention relates to certain details of construction by which the body is effectively adapted for use in either of two opposed positions.

Our invention further relates to arrangements and combinations of parts which will be hereinafter described and more particularly pointed out in the appended claims.

A preferred form of the invention is shown in the drawings, in which

Fig. 1 is a side elevation of our improved go-cart or carriage;

Fig. 2 is a partial side elevation of the carriage with the body reversed;

Fig. 3 is an enlarged detail elevation of a fastening device;

Fig. 4 is a detail plan view of the device, looking in the direction of the arrow 4 in Fig. 3;

Fig. 5 is an enlarged side elevation of a portion of the carriage body;

Fig. 6 is a detail end view of certain parts, looking in the direction of the arrow 6 in Fig. 5;

Fig. 7 is a detail plan view of certain parts, looking in the direction of the arrow 7 in Fig. 5;

Fig. 8 is a partial sectional elevation, taken along the line 8-8 in Fig. 5;

Fig. 9 is a view similar to Fig. 8 but showing the parts in a different position, and

Fig. 10 is a detail bottom view, looking in the direction of the arrow 10 in Fig. 8.

Referring to the drawings, we have shown a child's carriage or go-cart comprising running-gear G, a body B and a top T. The top T is mounted on the body B and may be secured in different angular positions thereon. The body B and top T, as a unit, are detachably supported on the running-gear G and may be positioned either as shown in Fig. 1 or as shown in Fig. 2 to suit the convenience and preference of the user. The front or foot portion of the body B may be dropped, as indicated in dotted lines in Fig. 1, when a child is to be supported in a sitting position.

The running-gear or main frame structure is in general of a folding type and comprises wheels 20 supported on cross rods secured to the lower ends of frame members 21 and 22. These frame members are pivotally connected at 23, and the frame members 22 are provided with rearward extensions 24 supporting a handle bar 25.

Each part 24 is pivoted at 26 to one end of a side bar 30. Each frame member 21 is connected by a link 31 to a pivot 32 near the opposite end of the side bar 30. A parallel link 33 is pivoted at its lower end to each frame member 22 and at its upper end to the corresponding link 31.

A stop pin 34 in each bar 30 limits the upward swinging movement of the link 31. A depending lug or projection 35 is fixed to each side bar 30 and is connected by a folding brace member 36 to a point 37 on the frame extension 24.

This folding frame-work, in substantially the form shown and described, is of a commercial type and in itself forms no part of our present invention, which relates to details of construction of the body B and to the means provided for detachably and reversibly securing the body to the running-gear or main frame structure.

The body B is preferably formed with an upper frame member 40 (Fig. 2) which extends along both sides and across the foot end of the body. An enclosing canvas cover or casing 41 is secured to and supported by the frame member 40 and forms the sides and foot end as well as a portion of the bottom of the body.

A seat 42 (Fig. 5) is provided at the opposite or head end of the body, and a back 43 is mounted at the outer end of the seat 42. The details of construction of the connection 5 between the seat and back will be hereinafter described.

The body B is provided with supporting studs 50 (Figs. 3 and 4) secured to the frame member 40 and projecting outward at each 10 side of the body. Each stud 50 is provided with a swivel head or locking member 51.

The side bars 30 are provided with slots 52 suitably spaced to receive the studs 50 and arranged substantially symmetrical with respect to the pivotal connection 23 of the 15 running-gear frame members 21 and 22.

A cross bar 60 (Figs. 9 and 10) is secured to the running-gear frame members 21 and 22 by the pivot studs 23 and extends across 20 the carriage underneath and adjacent the inward edge of the seat 42.

A cross bar 62 (Fig. 9) is secured to the under side of the seat 42, and the ends of the cross bar 62 are turned downward, as indicated at 63, and are provided with openings 64. When the parts are assembled, the down-turned end portions 63 of the cross bar 62 project downward through openings 65 in the cross bar 60. Locking bolts or plungers 30 66 are slidably mounted in bearing plates 67 secured to the under side of the cross bar 60. The outer ends of these plungers 66 are tapered, as indicated in the drawings, and are adapted to readily enter the openings 64 35 when the parts are in the assembled relation indicated in Figs. 8 and 10.

The inner ends of the plungers 66 are pivotally connected to a handle 70, which in turn is secured by a stud 71 to the under side of 40 the cross-bar 60. By swinging the handle 70 in one direction, the plungers may be simultaneously withdrawn, and by swinging the handle in the opposite direction, the plungers may be simultaneously pushed outward 45 to lock the seat 42 to the cross-bar 60.

The back 43 is provided with plates 80 (Fig. 6) secured to the lower corners of the back and each provided with upper and lower studs 81 and 82. Angle brackets 84 are 50 secured to the outer end portions of bars 85, extending under and secured to the seat 42. The angle brackets 80 are provided with slots 86 (Fig. 5) for the studs 82, and with notches or recesses 87 and 88 in the upper edge of the 55 brackets to receive the studs 81.

The back 43 may be readily adjusted in the brackets 84 by pulling the back upward and then swinging it forward or rearward so that the studs 81 are seated in desired recesses 60 87 or 88. The back may thus be effectively held in either a seated or a reclining position.

A bar 90 extends across the vehicle adjacent the outer edge of the seat 42 and may be secured to the end portions of the bars 85. 65 The outer ends of the bar 90 are offset up-

wardly, as indicated at 92, and the lower end of a chain or other flexible supporting member 93 is secured to each up-turned portion 92 by a bolt or stud 94. The upper ends of the chains 93 are secured by bolts or rivets 96 to 70 the upper frame member 40.

The outer edge of the seat 42 is thus directly supported from the upper frame member 40 and the weight of the occupant does not rest to any considerable extent on the flexible 75 casing 41.

The back 43 is supported entirely at its lower end by the seat 42, so that any rearward pressure applied to the back would tend to cause the front portion of the seat 80 42 to swing upward about the bolts 94 as a pivotal axis.

In our construction, however, the inward portion of the seat is held from upward movement by the plungers 66 and consequently any reasonable pressure may be exerted against the back 43 without causing displacement of the seat 42.

When the body B is to be removed from the running-gear, the handle 70 is turned to 90 withdraw the plungers 66, and the locking members 51 are turned to pass freely through the slots 52 in the side bars 30. The body and top may then be removed as a unit by springing the side bars apart, and may be 95 replaced in reverse position if desired, in which position they may be secured by turning the locking members 51 crosswise and projecting the plungers 66 outward.

The provision of chains or similar flexible 100 members 93 for supporting the outer edge of the seat is of particular advantage, as such chains will yield in any direction when the carriage is folded, regardless of whether the body is in the position shown in Fig. 1 105 or in the position shown in Fig. 2.

Having thus described our invention and the advantages thereof, we do not wish to be limited to the details herein disclosed, otherwise than as set forth in the claims, 110 but what we claim is:—

1. In a child's carriage, a running-gear having body-supporting side bars and a cross bar, a body having an upper frame member and a seat, means to detachably and reversibly secure said frame member to said side bars and the inner edge portion of said seat to said cross bar, locking devices to hold said seat and cross bar in selected assembled relation, and means to operate said devices simultaneously.

2. In a child's carriage, a running-gear having body-supporting side bars and a cross bar, a body having an upper frame member and a seat, and means to detachably and reversibly secure said frame member to said side bars and the inner edge portion of said seat to said cross bar, said means comprising apertured lugs on the seat insertable in slots in the cross bar, locking bolts on said 125 130

cross bar, and a handle for moving said bolts simultaneously in opposite directions toward or away from said lugs.

3. In a child's carriage having a running-gear, a body with an upper frame member secured in said running gear, a flexible body casing and a seat supported by said casing, in combination, a back mounted on the outer edge of said seat and entirely supported thereby, and means to detachably secure the inner edge portion of said seat to a portion of said running gear, whereby tipping of said seat by pressure against said back is prevented.
- 15 4. In a child's carriage having a running-gear, a body with an upper frame member secured in said running gear, a flexible body casing and a seat supported by said casing, in combination, a back mounted on the outer 20 edge of said seat and entirely supported thereby, means to detachably secure the inner edge portion of said seat to a portion of said running gear, whereby tipping of said seat by pressure against said back is prevented, and non-extensible flexible connections from said upper frame member to the 25 outer part of said seat, whereby the strain on said flexible body is relieved while said body remains freely foldable.
- 30 In testimony whereof we have hereunto affixed our signatures.

CARL J. BJORSON.

DONALD W. SIEBERT.

AARON A. GREENWOOD.
